(57) **CLAIM**

The ornamental design for a gaming machine as shown and described.

DESCRIPTION

FIG. 1 is a front perspective view of an exemplary gaming machine in accordance with the new design.

FIG. 2 is a front view of the gaming machine shown in FIG. 1.

FIG. 3 is a rear view of the gaming machine shown in FIG. 1.

FIG. 4 is a left side view of the gaming machine shown in FIG. 1.

FIG. 5 is a right side view of the gaming machine shown in FIG. 1.

FIG. 6 is a top view of the gaming machine shown in FIG. 1; and,

FIG. 7 is a bottom view of the gaming machine shown in FIG. 1.

The broken lines shown in the drawings are for the purpose of illustrating portions of the gaming machine that form no part of the claimed design.

1 Claim, 7 Drawing Sheets

Related U.S. Application Data

is a continuation of application No. 29/764,916, filed on Jan. 4, 2021, now Pat. No. Des. 964,471, which is a continuation of application No. 29/679,388, filed on Feb. 5, 2019, now Pat. No. Des. 908,802, which is a continuation of application No. 29/631,037, filed on Dec. 27, 2017, now Pat. No. Des. 843,482.
